DESIGN FOR A TRAFFIC SIGNAL CASING

Joseph W. Gosling, Schenectady, N. Y., assignor
to General Electric Company, a corporation of
New York

Application March 1, 1935, Serial No. 55,670

Term of patent 14 years

To all whom it may concern:

Be it known that I, Joseph W. Gosling, a citizen of the United States, residing at Schenectady, in the county of Schenectady, State of New York, have invented a new, original, and ornamental Design for a Traffic Signal Casing, of which the following is a specification, reference being had to the accompanying drawing forming a part thereof.

In the accompanying drawing Fig. 1 illustrates

a perspective view illustrating a side and the back of an ornamental traffic signal casing, and Fig. 2 is a top view of the same casing embodying my new design.

I claim:

The ornamental design for a traffic signal casing as shown.

In witness whereof, I have hereunto set my hand.

JOSEPH W. GOSLING.
